UNITED STATES PATENT OFFICE.

MARTIN VAN BUREN SMITH, OF NEW YORK, N. Y.

MEANS FOR PRODUCING AND DISTRIBUTING COMBUSTIBLE GASES.

No. 868,717.

Specification of Letters Patent.

Patented Oct. 22, 1907.

Application filed November 30, 1906. Serial No. 845,583.

To all whom it may concern:

Be it known that I, MARTIN VAN BUREN SMITH, a citizen of the United States of America, and a resident of the city, county, and State of New York, have invented certain new and useful Improvements in Means for Producing and Distributing Combustible Gases, of which the following is a specification, reference being had to the accompanying drawings, forming a part thereof.

- 10 My invention relates to means for producing and distributing combustible gases, and particularly to means for producing and distributing a combustible mixture of air and gas, the gas being generated from bituminous coal in a gas producer.
- 15 In carrying out my invention I employ a gas producer, a cooler and scrubber for the gases produced, and a blower and mixer for admitting and mixing air with the gas which has been evolved in the producer and after it has been cooled in the scrubbing and cooling device; and I preferably employ means for admitting air to the gas producer in direct proportion to the amount of air admitted for mixture with the evolved gases, together with means for regulating the relationship of the two said supplies.
- 20 My invention also relates to an improved means for sealing the connection between the producer and the scrubber at will, together with many other novel features of construction and combination of parts as will hereinafter be more fully set forth, and, in order that my invention may be fully understood, I will now proceed to describe an apparatus constituting an embodiment of same, having reference to the accompanying drawings in which said embodiment is illustrated, and will then point out the novel features in claims.
- 25 In the drawings: Figure 1 is a view in partial side elevation and partial vertical section of the apparatus. Fig. 2 is a detail view in central vertical section through the lower portion of the scrubber, showing the seal for the connection therewith from the producer.
- 30 Fig. 3 is a top view of the apparatus. Fig. 4 is a view in horizontal section of the producer, the plane of section being taken substantially upon the line 4-4 of Fig. 7. Fig. 5 is another horizontal sectional view of the producer, the plane of section being taken substantially upon the line 5-5 of Fig. 7. Fig. 6 is a detail view in longitudinal section of a part of the distributing pipe, showing particularly one of the safety screens employed therein. Fig. 7 is a view of the apparatus partially in elevation, with the producer shown in central vertical
- 35 transverse section. Fig. 8 is a detail view on an enlarged scale and in central longitudinal section of a portion of the automatic stoker employed, including the wind box. Fig. 9 is a view in transverse section therethrough. Fig. 10 is a detail view in central longitudinal section of the mixer employed. Fig. 11 is a view
- in transverse section therethrough. Figs. 12 and 13 are detail sectional views of the twyers employed in the producer.
- 40 The gas producer comprises a structure which encloses a furnace chamber 20, a dome 21 being provided at the top of said chamber, said dome having an opening 22 which opens into a chamber 23. The chamber 23 is closed ordinarily at the top by a cover 24, and at the side is provided with an opening 25 leading into a conduit 26, which conducts gas evolved in the furnace 20 into the scrubber 27.
- 45 The furnace 20 is preferably supplied with fuel automatically by means of an automatic stoker, said stoker including a feed chamber 28 having its upper portion directly open into the furnace 20, a feed screw conveyor 29, a hopper 30 and a wind box 31. The wind box communicates with the interior of the furnace through draft openings 36, as will be more clearly understood by reference to Figs. 7, 8 and 9 of the drawings. The wind box 31 receives air from a suitable source through a supply pipe 32, said supply pipe being also provided with a branch 33, which supplies air to the twyers 34 such as are ordinarily provided in producers, and which may be of any suitable form and construction. The furnace is also preferably provided with poke holes 35 arranged near the upper end, through which the material contained therein may be poked and inspected.
- 50 The scrubber 27 may be of any suitable form, being here shown as provided with five compartments 36, 37, 38, 39 and 40. The compartments 37, 38 and 39 contain pebbles of varying sizes, the compartment 37 containing the largest pebbles, and the compartment 39 the smallest. The compartment 40 contains tan bark. The said compartments are divided the one from the other by means of perforated diaphragms or screens 41. Water is admitted into the chamber 39 through a suitable sprinkling device 42, the water percolating through the said chambers 39, 38, 37 clear to the bottom chamber 36. A drain 43 is arranged for the purpose of discharging water from the bottom chamber 36, the water in said chamber being normally at the level shown in Fig. 1 of the drawings. The said chamber 36 is a gas receiving chamber, and receives gas as it is discharged from the conduit 26. The lower end of the conduit 26 penetrates some distance into the said chamber 36, as will be readily understood by reference to Figs. 1 and 2 of the drawings. If it is desired for any purpose to seal the bottom of the conduit 26, the water may be allowed to rise in the chamber 36, as is shown in Fig. 2. As a simple means for accomplishing this, I have provided a by-pass 44 in the drain 43 and a valve 45; by closing the valve 45 the water, in passing through the drain 43, will be compelled to pass around the by-pass 44,—this will cause 11

the level of the water in the chamber 36 to rise from that shown in Fig. 1 to that shown in Fig. 2, the level shown in Fig. 2 being substantially the level of the upper horizontal member of the by-pass 44. This means for sealing the lower end of the conduit 26 will be found useful on many occasions, such, for instance, as when it is desired to first start up the producer. In so starting up, or whenever else it may be desired, the cover 24 may be removed, and, if the lower end of the conduit 26 is sealed before the cover 24 is removed, there will be no chance of gas backing up through the conduit 26 and escaping through the opening thereby made. The furnace may now be blasted up in the usual way, and, when the gas begins to evolve, the cover 24 may be placed in position and the seal for the conduit 26 broken by the opening of the valve 45.

The gas received from the producer in the chamber 36 passes up through the various scrubbing chambers, and is finally discharged from the top of the scrubber 27 through a pipe or conduit 46 to a mixer 47. The mixer 47 comprises an inlet chamber 48 for receiving the gas from the pipe or conduit 46, a chamber 49 for receiving air from a suitable air supply pipe 50, a mixing chamber 51, a plurality of tubes 52 for delivering the gas received in the chamber 48 into the said chamber 51, and a plurality of tubes 53 for delivering the air received in the chamber 49 into the mixing chamber 51, the said air and gas being thoroughly mixed in the mixing chamber 51, and finally discharged into a main distributing pipe or conduit 54.

The main distributing pipe or conduit may be of any suitable length and form, and it is the purpose of my present invention to lead the same to various points at which the combustible mixture of gas and air may be delivered for commercial purposes, such as heat, light and power. Adjacent to the different points at which the combustible mixture is so discharged, I provide safety screens, one of which is shown in detail at 55 in Fig. 6. These safety screens are, of course, intended for preventing a flame from flashing back into the conduit and causing an explosion therein or in the scrubber, but, in case an explosion does occur at any point, I have provided a number of safety blow-offs 56, or flash doors as they are sometimes called. I have not only provided these at different points along the conduit 54, but I have also provided the various chambers 37, 38, 39 and 40 of the scrubber with such doors. Those doors are normally kept closed by weights or springs, but will yield to relieve an excess of pressure. I also preferably provide the end of the line comprising the main distributing conduit 54 with a safety valve 57, so that, in case an excess quantity of gas and air is received therein, an escape for the same will be permitted as the pressure rises above a predetermined point.

I have provided means for supplying air to the air supply pipes 32 and 50 in blowers 58 and 59. These blowers are herewith shown as set side by side and driven from the same shaft 60; the said shaft being driven from an internal combustion engine 61 which may conveniently receive its motive fluid from the main distributing conduit 54. Suitable valves 62 and 63 may be employed to control the supply of air from the blowers 58 and 59 respectively, and valves 64 and 65 are further provided to control the inlet of air to the said blowers.

The said valves may be employed to control the relative quantity of air supplied from the blowers to the producer chamber on the one hand, and the mixer on the other. By this means the proportion of air delivered to the producer may be properly regulated with respect to the proportion of air delivered to the mixing chamber, and, once this proportion is properly regulated, the same proportion will be maintained, as will be readily understood.

It will be noted that I have placed the producer on a lower level than the rest of the apparatus. This is a preferred construction, in order to provide that the conduit which leads from the top of the producer to the bottom of the scrubber shall be as short as possible.

From the foregoing, it will be seen that I have devised a completely automatic system for generating, supplying and distributing a combustible gas for heat, light and power purposes. The quality of the mixture may be easily regulated, and, when so regulated, will be maintained so as to be uniform. The device which acts to scrub and cleanse the gas as it comes from the producer also acts as a cooling means; the gas leaving the scrubber at about the temperature of the incoming water. Thus the gas, when presented for mixture with the air, will be quite cool, and such mixture will be entirely safe. The peculiar arrangement of the mixer is such as to effect a thorough mixing, as will be readily understood, and the safety devices, including the flash doors, safety valve and safety screens will positively prevent any serious accident through explosions or from excess of pressures from any cause.

What I claim is:

1. Means for producing and distributing combustible gases comprising a gas producer, a cooler, a main distributing conduit, a mixer between the delivery from the producer and the said main distributing conduit, and means for delivering air to the producer and a proportionate quantity of air to the said mixer for mixing with the gas passing therethrough.

2. The combination with a gas producer, of means for supplying air thereto and for mixing a directly proportionate quantity of air with the gas evolved therein after it has passed away from the producer, a distributing conduit for distributing the combustible mixture of gas and air to various points for commercial purposes, and safety screens in proximity to each point at which the said combustible mixture is delivered for use.

3. The combination with a gas producer and means for supplying air thereto, of means, in connection with the first said means, for mixing air with the gas evolved in the producer after the gas has left same and for distributing the combustible mixture of gas and air so produced to various points for commercial purposes.

4. The combination with a gas producer and means for supplying air thereto, of means for mixing air with the gas evolved in the producer after it has been discharged therefrom, and means for regulating the amount of air supplied to the producer proportionately to the amount of air later supplied for mixing purposes.

5. The combination with a gas producer, cooling means for cooling the gas so produced, and a blower for supplying air under pressure to the producer, of a mixer for receiving cooled gas, and a blower for supplying air under pressure to the mixer.

6. The combination with a gas producer, cooling means for cooling the gas so produced, and means for supplying air under pressure to the producer, of a mixer for receiving cooled gas, means for supplying air under pressure to the mixer, and means for regulating the amount of air supplied to the producer proportionately to the amount of air supplied to the mixer.

7. The combination with a gas producer comprising a

furnace chamber, and automatic fuel feeding means, the latter including a wind box, of means for receiving and cooling the gas evolved in the producer, a mixer for receiving the gas from the cooling means, and means for supplying air under pressure to the wind box and to the mixer in predetermined proportions.

8. The combination with a gas producer comprising a furnace chamber, and automatic fuel feeding means, the latter including a wind box, of means for receiving and

cooling the gas evolved in the producer, a mixer for receiving the gas from the cooling means, means for supplying air under pressure to the wind box, and means for regulating the supply of air delivered to the said wind box proportionately to the supply of air delivered to the mixer.
